UNITED STATES PATENT OFFICE.

WALTER F. KOKEN, OF WEBSTER GROVES, MISSOURI.

ELECTRIC SWITCH.

Application filed July 26, 1924. Serial No. 723,391.

This invention relates to electric switches, and has for its main object to provide an inexpensive switch of novel construction, which is of such design that the contacts 5 will be separated and closed with a quick break, thereby preventing the contacts from being burned or rendered defective, due to arcing of the electric current.

To this end I have devised a switch, 10 which, in its simplest form, consists of a toggle operatively connected with the movable contact of the switch, a spring combined with said toggle in such a way as to normally hold the toggle broken, namely, 15 with the members of the toggle disposed at an angle to each other, and an operating member that is adapted to be moved in a direction to straighten the toggle, said spring being combined with the toggle in 20 such a way that it imparts a sudden movement to the toggle members when they reach a certain position during the operation or straightening the toggle, and thereby causes the contacts to be separated or 25 closed with a quick break, depending upon the direction in which the operating member is moved. My invention is applicable to various kinds of switches, either switches 30 of the type in which the operating member is moved manually in opposite directions so as to open and close the circuit which the switch governs, or switches of the type in which the operating member is normally under the influence of a spring that tends to 35 move and hold said operating member in one position.

Figure 1 of the drawings is a side elevational view of a switch constructed in accordance with my invention that is adapted 40 to be used for closing an electric circuit in any one of a plurality of different positions of a controlling member, showing the movable contact of the switch open.

Figure 2 is a similar view, showing the 45 movable contact closed.

Figure 3 is a transverse sectional view, taken on the line 3—3 of Figure 1; and

Figure 4 is a side elevational view of a 50 switch embodying my invention, in which the operating member is adapted to be moved manually in opposite directions to close and open the circuit.

In the drawings, which illustrate the preferred form of my invention, A designates 55 the movable contact of the switch and B

designates the stationary contact, the stationary contact being herein illustrated as composed of two conducting rings arranged in an electric circuit x , and the movable contact A being herein illustrated as a bar 60 that is adapted to engage both of said conducting rings so as to complete the circuit by bridging the space between said conducting rings. It is obvious, however, that the movable contact might consist of a member 65 connected to one side of an electric circuit and arranged to move into and out of engagement with a single stationary contact connected to the other side of the circuit.

The movable contact A is moved towards 70 and away from the stationary contact to close and open the circuit by a mechanism that comprises a toggle composed of two links 1 and 2 pivotally connected together at 3, a contractile spring 4 or a plurality of 75 contractile springs connected to the toggle links 1 and 2, and an operating member 5 combined with said toggle links in such a way that when said operating member is moved in one direction the contacts A and 80 B will be separated with a quick break, and when said operating member 5 is moved in the opposite direction, the movable contact will snap into engagement with the stationary contact. The particular form or details 85 of construction of the toggle members 1 and 2 is immaterial, so far as my broad idea is concerned, but I prefer to construct said members in the form of two flat links, formed from sheet metal stampings, that are 90 arranged between a pair of parallel plates or supporting members C to which both of said links are pivotally connected by the pivot pin 3, previously referred to that joins the links 1 and 2 together. Two contractile 95 springs 4, which are arranged on the outside of the supporting plates C, are connected at one end to laterally-projecting extensions on the outer end of the link 1 and connected at their opposite ends to similar laterally-projecting extensions 2^a at the outer end of the 100 toggle link 2, as shown in Figure 3. Normally, the springs 4 exert pressure on the toggle links 1 and 2 in a direction to hold the toggle broken either with the outer ends 105 of the links 1 and 2 inclined downwardly, and with the springs 4 arranged below the pivot 3, as shown in Figure 2, or with the outer ends of said links inclined upwardly and the springs 4 arranged above the pivot 110

3, as shown in Figure 1. The movable contact A of the switch is carried by the toggle link 1 and is preferably pivotally mounted on the outer end of said link 1 in such a way
5 that said movable contact A will bear evenly or squarely on the stationary contact B, notwithstanding the fact that said movable contact A is carried by a pivotally mounted member. In the switch herein illustrated
10 the movable contact A is secured to a block of insulating material 6 that is fastened to a reciprocating contact carrier 7 provided with a shank 8 pivotally connected at its upper end by a pin 9 to ears 10 on the toggle link 1, the stationary side plates C between which said toggle link is arranged being equipped with guides 11, as shown in Figure 1, that co-operate with the shank 8 on the movable contact carrier 7 to cause said carrier to reciprocate in a straight path during the operation of moving the contact A into and out of engagement with the stationary contact B, said guides 11 also serving as stops which limit the movement of the
25 contact carrier 7 when it is moving in a direction to separate the contacts.

The operating member 5 of the switch, previously referred to, is arranged between the side plates C to which it is pivotally connected by a pivot 12, and the inner end of said member 5 is joined to the outer end of the toggle link 2 by a short link 12^a, as shown more clearly in Figure 2. As previously stated, it is immaterial whether the
30 operating member 5 consists of a part that is adapted to be moved in one direction by a spring which normally holds said member in one position and adapted to be moved manually in the opposite direction, or whether said member consists of a part that is adapted to be moved manually in opposite directions. In Figures 1 to 3 of the drawings I have illustrated the operating member 5 as consisting of a part combined with two
35 springs 13 that exert pressure on said member in a direction tending to move the contact A towards the stationary contact B, said operating member 5 being adapted to be moved in the opposite direction so as to separate the contacts by a manually-operated device, herein illustrated as a spring-actuated plunger 14, carried by a controlling member D and arranged so that when it is pushed
40 downwardly by exerting pressure on a handle 14^a, at the upper end of said plunger, the inner end of the operating member 5 will swing upwardly, thereby causing the link 12^a to move the toggle links 1 and 2 in a direction to straighten same, and thus cause
45 the springs 4 to impart a sudden upward movement to said toggle links when said springs pass the center of the pivot 3 which joins the inner ends of said toggle links together, thereby separating the contacts with a quick break. The springs 13 that are

used to move the operating member 5 in one direction can be arranged in various ways without departing from the spirit of my invention, but in the switch shown in Figures 1 and 2 said springs are connected at their lower ends to pins on the supporting plates C and connected at their upper ends to the free end of the toggle link 2, thereby causing the toggle links to be normally under the influence of a resilient means which constantly exerts pressure on same in a direction tending to hold the toggle links 1 and 2 in the downwardly-inclined position they assume when the circuit is closed.

In the form of my invention illustrated in Figure 4 the operating member 5^a of the switch is not combined with a spring or springs similar to the springs 13, but instead, is adapted to be moved manually in one direction by pressure exerted downwardly on the outer end of said member 5^a and adapted to be moved in the opposite direction by pressure exerted upwardly on the outer end of said member. In the switch shown in Figure 4 the operating member 5^a is held in either one of its extreme positions by the tension of the springs 4 connected with the toggle links 1 and 2. Accordingly, in the switch shown in Figure 4 the movable contact A will be held in its open position so long as the springs 4 are arranged above the pivot 3 of the toggle, as shown in Figure 1, and will be held in its closed position in engagement with the stationary contact B when said springs 4 are arranged below the pivot 3 of the toggle, as shown in Figure 2.

The switch shown in Figures 1 and 2 is intended to be used for enabling an electric circuit to be opened and closed in any one of a plurality of positions of a controlling member. The controlling member D is herein illustrated as consisting of a lever or handle D secured to the outer end of a rock shaft 15 that turns in a stationary bearing 16 which is provided at one end with a flange 17 that has a plurality of deep notches 18 and a shallow notch 18^a formed in same. The supporting plates C, previously referred to, are rigidly connected to the hub of the lever D, and the operating member 5 of the switch is arranged so that it will co-operate with the notched flange 17 on the stationary bearing 16 to hold the lever D in various positions. When the controlling lever D is arranged in its neutral position the operating member 5 is positioned in the shallow notch 18^a and the movable contact A of the switch will be held in its open position because said shallow notch prevents the operating member 5 from moving far enough under the influence of the springs 13 to permit the springs 4 to move downwardly below the pivot 3 of the toggle, and thus swing the toggle levers 1 and 2 downwardly.

- When it is desired to move the controlling member D into any one of its operative positions the handle 14^a at the upper end of the spring-pressed plunger 14 is moved downwardly so as to swing the inner end of the operating member 5 upwardly, thereby causing said member 5 to be withdrawn from the shallow notch 18^a, after which the controlling member D can be swung to the right 10 or to the left into such a position that the operating member 5 will align with one or the other of the deep notches 18. When said operating member moves into alignment with one of said deep notches, the 15 springs 13 exert pressure on the toggle link 2 in a direction to pull said link downwardly, whereupon the member 5 will move into said deep notch, and both of the toggle links will swing downwardly below the pivot 3, 20 due to the pressure which the springs 4 exert on said toggle links, thereby causing the contact A to move with a quick stroke into engagement with the stationary contact B. When it is desired to open the circuit the 25 operator pushes downwardly on the handle 14^a on the plunger 14, thereby causing the member 5 to move upwardly out of engagement with the deep notch in the flange 17 and causing the outer end of the toggle 30 link 2 to swing upwardly, whereupon the springs 4 will impart a quick upward movement to the toggle link 1 when the springs 4 pass the pivot of the toggle, and thus cause the contacts to be separated with a quick break. 35 A switch of the construction above described is inexpensive to manufacture as it is composed of a few simple parts of rugged design; it is reliable in operation; and as the contacts are opened and closed with a 40 quick break, the contacts are not liable to be burned or rendered defective by arcing of the electric current.

Having thus described my invention, what I claim as new and desire to secure by Letters Patent is:

1. An electric switch, comprising a movable contact, a supporting structure, two toggle links pivotally connected to said supporting structure by a pivot pin that also 50 joins the inner ends of said links together, the outer ends of said links being free to move, contractile springs connected to the free end portions of said links, a pivotally mounted operating member on said supporting structure, a connection between said operating member and one of said toggle links, and a connection between the other toggle link and the movable contact.
2. An electric switch, comprising a movable contact, two supporting plates arranged 60 in parallel relation, a pair of toggle links arranged between said plates, and pivotally connected at their inner ends to same by a pivot pin on which both of said links rock, 65 the outer ends of said links being free to move, contractile springs connected to the free end portions of said links, means for holding 70 said links in an angular position with the springs located at one side of said pivot pin, a shank on the movable contact pivotally connected to one of said links, and a pivotally mounted operating member on said plates joined to the other toggle link.
3. An electric switch, comprising a movable contact, a carrier for said contact provided with a shank, a supporting structure provided with guides that co-operate with said shank to cause said contact to move in a straight path, a pivotally mounted operating member on said structure, a pair of toggle links having their inner ends pivotally connected together and also pivotally connected to said supporting structure, a pivotal connection between said operating member and the free end of one of said links, a 75 pivotal connection between the free end of the other link and the shank of said contact carrier, and a spring attached to the free ends of said links for imparting a quick stroke to said contact carrier to open or 80 close the circuit, depending upon the direction of movement of the operating member.
4. An electric switch, comprising a movable contact, a supporting structure, a spring-actuated toggle composed of a pair 85 of links having their inner ends pivotally connected to said supporting structure, a spring-pressed, rockable operating member on said structure, a connection between said operating member and the free end of one 90 of said links, and means for pivotally mounting said contact directly on the free end of the other toggle link.
5. An electric switch, comprising a movable contact, a supporting structure, a rockable member pivotally connected at one end of said supporting structure, means for pivotally mounting said contact on the opposite end or free end of said rockable member, a second rockable member pivotally connected at one end to said structure, means for effecting a change in the position of the rockable member last referred to, and a resilient means combined with said rockable members in such a way that it imparts a quick stroke 100 to the rockable member which carries the contact when the other rockable member is shifted into a different position.
6. An electric switch, comprising a movable contact, a supporting structure, a toggle composed of two links pivotally mounted on said supporting structure and having their ends pivotally connected together, contractile springs connected to the free end 110 portions of said links, means for mounting 115 said contact on the free end of one of said links, independent contractile springs connected to said supporting structure and to the free end of the other toggle link, and a pivotally mounted operating member on said 120 links.
7. An electric switch, comprising a movable contact, two supporting plates arranged in parallel relation, a pair of toggle links arranged between said plates, and pivotally connected at their inner ends to same by a pivot pin on which both of said links rock, 125 the outer ends of said links being free to move, contractile springs connected to the free end portions of said links, means for mounting 130 said contact on the free end of one of said links, independent contractile springs connected to said supporting structure and to the free end of the other toggle link, and a pivotally mounted operating member on said links.

supporting structure for moving said toggle links in a direction to straighten the toggle.

7. An electric switch, comprising a movable contact, a supporting structure, a rockable member pivotally connected at one end to said supporting structure, a resilient means that normally exerts pressure on said rockable member in one direction, means for moving said rockable member in opposition to said resilient means, a second rockable member having one of its ends pivotally connected to said structure and its opposite end pivotally connected to said movable contact, and a contractile spring combined with said rockable members in such a way as to impart a quick stroke to the rockable member which carries the contact when the other rockable member is moved into certain positions.

8. An electric switch, comprising a movable contact, a shiftable controlling member that is adapted to be rocked into various positions, a supporting structure on said controlling member that moves bodily with same, a spring-actuated toggle on said supporting structure for imparting a quick stroke to said contact during the operation of moving it into and out of its closed position, said contact being pivotally mounted on one member of said toggle, an operating member on said supporting structure that is used to actuate said toggle, and a means that co-operates with said operating member to hold said controlling member at rest.

9. An electric switch, comprising a stationary contact, a movable contact, a shiftable controlling member that is adapted to be arranged in a neutral position and in a plurality of operative positions, a spring-actuated toggle carried by said controlling member and arranged to impart a quick stroke to said movable contact towards said stationary contact when said controlling member reaches any of its operative positions, and means for holding said movable contact spaced away from said stationary contact when said controlling member is in its neutral position.

10. An electric switch, comprising a stationary contact, a movable contact, a shiftable controlling member that carries said movable contact, means for holding said controlling member in a neutral position and in a plurality of operative positions, a spring-actuated toggle for imparting movement to said movable contact, and means for causing said toggle to move said movable contact into engagement with the stationary contact when said controlling member is arranged in either of its operative positions and for causing said movable contact to be held spaced away from said stationary contact when the controlling member is in its neutral position.

11. An electric switch, comprising a stationary contact, a movable contact, a shiftable controlling member that carries said

movable contact, a movable operating member on said controlling member, a spring-actuated toggle interposed between said operating member and said movable contact, and means arranged adjacent the path of movement of said controlling member that is adapted to co-operate with said operating member to hold said controlling member in a plurality of different positions.

12. An electric switch, comprising a stationary contact, a movable contact, a rockable controlling member, a supporting structure on said controlling member, a stationary rack, a pivotally mounted device on said supporting structure that is adapted to co-operate with said rack to hold said controlling member in different positions, a spring that exerts pressure on said pivotally mounted device in a direction to move it towards said rack, and a spring-actuated toggle interposed between said device and said movable contact for moving said contact towards and away from the stationary contact.

13. An electric switch, comprising a stationary contact, a movable contact, a rockable controlling member, a supporting structure on said controlling member, a stationary rack, a pivotally mounted device on said supporting structure that is adapted to co-operate with said rack to hold said controlling member in different positions, a spring that exerts pressure on said pivotally mounted device in a direction to move it towards said rack, a spring-actuated toggle interposed between said device and said movable contact for moving said contact towards and away from the stationary contact, and a manually-operable means on said controlling member for moving said pivotally mounted device in opposition to its actuating spring.

14. An electric switch, comprising a stationary contact, a movable contact, a rockable controlling member, a supporting structure on said controlling member, a stationary notched element, a pivotally mounted device on said supporting structure that is adapted to co-operate with said notched element to hold the controlling member in any one of a number of different positions, a pair of pivotally mounted toggle links on said supporting structure, contractile springs connected to the free end portions of said links, a pivotal connection between the movable contact and one of said toggle links, a connection between the other toggle link and the pivotally mounted device on the supporting structure, independent contractile springs connected to said supporting structure and to the toggle link to which said pivotally mounted device is connected, and a manually-operable, spring-pressed plunger on said controlling member for moving said pivotally mounted device in a direction to disengage it from said notched element.

WALTER F. KOKEN.
